UNITED STATES PATENT OFFICE.

EUGÈNE A. OSSÉLIN AND ABRAM MEYER, OF PARIS, FRANCE.

GALVANIC RING.

SPECIFICATION forming part of Letters Patent No. 230,194, dated July 20, 1880.

Application filed October 6, 1879.

To all whom it may concern:

Be it known that we, EUGÈNE ADOLPH OSSÉLIN, of Paris, France, (optician,) and ABRAM MEYER, of Syracuse, in the State of New York, United States of America, (optician,) have invented a new and useful Electric Ring Bracelet or Necklace, to be worn upon the person for ornamental or medicinal purposes; and we do hereby declare that the following is a perfect and exact description thereof.

The object of our invention is a ring, bracelet, or other article, constructed as fully described hereinafter, to secure a galvanic action under the influence of moisture, and to increase this action when desired.

In the drawings forming part of this specification, Figure 1 is a face view of a ring, showing our improvement; and Fig. 2, a plan, partly in section.

The body A of the ring, bracelet, or other article is of copper or other metal, or in some instances, as when a ring having a bezel is used, may be of a non-electric material.

The galvanic elements are two metals, c z, which are placed in juxtaposition, extending from the outer to the inner side of the article, so as to be in contact with the skin of the

wearer, the moisture of the skin insuring a galvanic action between the electro-positive and electro-negative metals. In order to increase this action we sometimes form recesses x in the article, in or between the two elements, and insert therein, in a powdered form, any suitable salt or other material which will act as an excitant; and in order to increase the effect we perforate the article at suitable points, y, so that moisture from the skin or air may enter the recess and moisten the salt.

A most convenient mode of embodying our invention is to apply the elements to the bezel of an ordinary ring, as shown in the drawings, thereby securing ample room for the salts.

We claim as our invention—

The ring provided with galvanic elements c z in the bezel with receptacles for an excitant salt, and having perforations x, substantially as specified.

In testimony whereof we have signed our names to this specification before two subscribing witnesses.

E. OSSÉLIN.
A. MEYER.
